MOUTHPIECE COVER FOR MUSICAL INSTRUMENTS

George Shaw, Brooklyn, Severino Frank Marino,
New York, and Daniel Shaw, Brooklyn, N. Y.

Application April 30, 1947, Serial No. 744,998

11 Claims. (Cl. 84—383)

1

The present invention relates to a device for musical instruments, and more especially to a protective cover for the mouth-piece thereof.

The object of the present invention is to provide a device which is inexpensive to manufacture, simple in structure, durable in operation, and which may be applied to the mouthpiece of a musical instrument with great ease and celerity.

Another object of the present invention is to provide a protective cover for the mouthpiece of wind instruments such as saxophones, clarinets and the like which may be quickly applied and removed therefrom without the possibility of displacing or destroying the reed thereon.

Musicians in some of the bands play more than one instrument, and in some instances, it becomes necessary for the musician to change from one instrument to another during the same orchestration, and in so doing the instruments must be ready to play immediately.

The reeds on the instruments must be very moist to produce sound, otherwise they are practically useless.

Attempts have been made to provide protective covering and moistening devices which were tubular types that slid over the end of the mouthpiece and removed in the same manner, and it has been found that when these covers are slid over the end of the mouthpieces they sometimes lift the end of the reed, and either displace or destroy it. There is considerable expense and loss of time in replacing damaged reeds at present, which the present invention obviates.

The present invention obviates these difficulties by providing a protective cover which may be wrapped around the mouthpiece of a wind instrument or clamped to the end thereof.

Other objects and advantages of the present invention will be obvious as brought out in following specification and claims.

Reference will be had to the accompanying drawings forming a part of this specification in which similar reference characters indicate corresponding parts throughout the several views, in which,

Fig. 1 is a perspective view of a conventional type of mouthpiece on a wind instrument.

Fig. 2 is a preferred embodiment of the present

invention, showing the wrap around cover in perspective,

Fig. 3 is a modified form of the cover,

Fig. 4 is a cross section taken on the line 4—4 of Fig. 3; and

Fig. 5 is a perspective view of a moistening pad.

Referring to the drawings wherein we have shown by way of illustration merely, a fragmentary portion 10 adjacent the mouthpiece 11, of a wind instrument such as a saxophone, clarinet or the like, wherein the mouthpiece 11 consists of the reed 12 and the conventional clamping device or ligature 13, for properly positioning the reed 12 on the mouthpiece 11.

15 The preferred embodiment of the present invention as illustrated in Fig. 2, consists of a tubular protective cover 14, comprising a semitubular portion 15 hingedly secured to another semitubular portion 16 by a spring hinge 17, which normally hold the parts 15 and 16 in the closed position as shown in Fig. 2.

The semitubular portion 15 has secured thereon a plate 19 which holds a moistening pad 21. The plate 19 is hinged to the semitubular portion 15 as shown at 20.

The tube 14 has an annular flange 18 at the outer end thereof to fix the position of the pad 21 in respect to the reed 12, when the tube 14 is wrapped around the mouthpiece 11.

30 In applying the protective cover 14 to the mouthpiece 11 of the instrument 10 it is only necessary for the musician to take hold of the flange 18 and open the semitubular portions 15 and 16 and thence wrap the tube around the 35 mouthpiece 11 by bringing it up from underneath and then closing the moistening pad 21 down on top of the reed 12.

If it is found desirable the hinge 20 may be a spring hinge to normally hold the pad 21 against the reed 12, so that the slight pressure of the spring will press the pad 21 against the reed 12, thereby insuring a complete moistening effect upon the reed 12.

40 A modified form of a protective cover is shown in Figs. 3 and 4, wherein in this instance the protective device comprises a clamp 22, consisting of a pair of rocking elements 23 and 24. The rocking element 23 has a jaw 25 at one end and an integral finger lever 27 at the other end. The 45 jaw 25 has a moistening pad 30 adhesively or

otherwise secured to the interior surface thereof. The rocking element 24 has a jaw 26 at one end and an integral finger lever 28 at the other end. The jaw 26 is shaped as shown at 32 to conform to the contour of the bottom of the mouthpiece 11.

The rocking elements 23 and 24 are connected by a spring 29 which normally holds the jaws 25 and 26 together. The jaws 25 and 26 may be opened by compressing the finger levers 27 and 28 at one end of the jaws 25 and 26.

When the instrument is not being played, the protective clamp 22 is secured to the mouthpiece 11 and reed 12 by opening the jaws 25 and 26 and placing it on the mouthpiece 11 and reed 12, so that the moistening pad 30 will rest upon the reed 12 and the cut out portion 32 of the jaw 26 will conform to the contour of the bottom of the mouthpiece 11.

In Fig. 5, we have shown a separate moistening pad 33 held on to a plate 34 by means of the rolled over edges 35 of the plate 34. The moistening pad 33 may be used in conjunction with the wrap around protective cover 14 as an alternate form when the pad 21 and plate 19 is left off of the cover 14. In this instance the edges 36 and 37 of the cover 14 may be brought together to touch on a line diametrically opposite to the hinge 17, and the pad is first placed upon the reed 12 before the protective cover 14 is wrapped around the mouthpiece 11.

It will be seen that when the cover 14 is wrapped around the mouthpiece 11, the opening 38 in the cover 14 will lie on each side of the clamping screws 39 of the clamp or ligature 13.

The novel feature of the present invention is to provide a protective cover for musical wind instruments which may be quickly applied to the mouthpiece thereof and quickly removed therefrom without endangering, or rupturing the reed thereof, which is so often the case, wherein a solid tubular cover is slid longitudinally over the end of the mouthpiece thereof.

It is very important, as brought out in the preamble of this specification, that the reed should be thoroughly saturated during an orchestration and the protective covers such as shown in Figs. 2, 3 and 4 may be quickly removed from the mouthpiece of a wind instrument without endangering, displacing or breaking of the reed, so that the musician may change from one instrument to another during the same orchestration.

It will of course be understood that the present invention could be modified to be applicable to wind instruments wherein the mouthpiece has a reed on the top and bottom thereof by simply providing a protective cover wherein there is secured a pad at the top and bottom thereof to cover a plurality of reeds.

We claim:

1. A protective cover for the mouthpiece of wind instruments comprising, a tube having a longitudinal hinge at the bottom thereof, a longitudinal opening diametrically opposite the aforesaid hinge, a flange at one end of said tube, and a plate carrying a moistening pad hingedly secured to one edge of the aforesaid opening and adjacent the aforesaid flange.

2. A protective cover for the mouthpiece of wind instruments comprising, a pair of rocking levers hingedly secured together with a pair of jaws at one end thereof and a pair of integral finger levers at the other end thereof, one jaw having a moistening pad secured thereto, the other jaw having the inside thereof shaped to

conform to the contour of the bottom of the mouthpiece of a wind instrument.

3. A protective cover for the mouthpiece of wind instruments having a reed comprising, a tube longitudinally hinged at the bottom thereof, an opening diametrically opposite said hinge substantially half the length of said tube with the remaining half of said tube having its edges substantially abutting each other, a flange at the outer end of said tube, and a separate moistening pad adapted to be placed upon the reed of the mouthpiece of said wind instrument before said tubular cover is placed thereon.

4. A protective cover for the mouthpiece of wind instruments comprising, a tube having a longitudinal spring hinge at the bottom thereof, a longitudinal opening diametrically opposite the aforesaid hinge, a flange at one end of said tube, and a plate carrying a moistening pad spring hingedly secured to one edge of the aforesaid opening and adjacent to the aforesaid flange.

5. A device of the kind described comprising, a pair of rocking levers hingedly secured together with jaws at one end thereof integral finger levers at the other end thereof, one jaw having a moistening pad secured thereto, the other jaw having the inside thereof shaped to conform to the bottom contour of the mouthpiece of a wind instrument.

6. A protective cover for the mouthpiece and reed of wind instruments comprising, a tube longitudinally spring hinged at the bottom thereof, and opening diametrically opposite said spring hinge substantially half the length of said tube with the remaining half of said tube having its edges substantially abutting each other, a flange at the outer end of said tube, and a separate moistening pad adapted to be placed upon the reed of the mouthpiece of said wind instrument before said tubular cover is placed thereon.

7. A protective cover for the mouthpiece and reed of wind instruments comprising, a tube having two semi tubular parts longitudinally hinged throughout the entire length of the bottom thereof, a longitudinal opening diametrically opposite the aforesaid hinge throughout the entire length of said tube, a flange at one end of said tube, and a plate carrying a moistening pad spring hingedly secured to one edge of the aforesaid opening and adjacent to the aforesaid flange.

8. A protective cover for the mouthpiece and reed of wind instruments, comprising, a tube having two semi tubular portions spring hingedly connected throughout the entire length of the bottom thereof, a turned in flange at one end of said tube, a longitudinal slot in said tube when said tube is closed running the entire length of said tube and diametrically opposite said hinged portion, a plate spring hingedly secured to the edge of one semi tubular portion to the edge of the longitudinal opening and adjacent to said flange, and a moistening pad secured to said plate and adapted to rest upon said reed with pressure when said tube is wrapped around said mouthpiece of said wind instrument.

9. A protective cover for a reed-equipped mouthpiece of wind musical instruments comprising a body having a plurality of parts hingedly secured together, one part of said body carrying a moistening device to engage the reed and adapted to fit on the mouthpiece.

10. A protective cover for a reed-equipped mouthpiece of wind musical instruments comprising a body having a plurality of parts spring hingedly secured together, one part of said body

carrying a moistening device to engage the reed
and adapted to fit on the mouthpiece.

11. A protective cover for a reed-equipped
mouthpiece of wind musical instruments com-
prising a body having a longitudinal hinge at
the bottom thereof, an opening at one end of
said body opposite said hinge substantially half
the length of said body with the remaining half
of said body opposite said hinge having edges
substantially abutting each other, a moistening
device secured to one edge of said body to engage
the reed and adapted to fit on the mouthpiece.
